UNITED STATES PATENT OFFICE.

GEORGE W. CARR, OF OSCEOLA, PENNSYLVANIA.

GATE-ACTUATING MECHANISM FOR ELEVATORS.

1,119,682.

Specification of Letters Patent.

Patented Dec. 1, 1914.

Application filed October 24, 1913. Serial No. 797,091.

To all whom it may concern:

Be it known that I, GEORGE W. CARR, a citizen of the United States, residing at Osceola, in the county of Tioga and State of Pennsylvania, have invented a new and useful Gate-Actuating Mechanism for Elevators, of which the following is a specification.

The present invention relates to improvements in gate actuating mechanisms for elevators, one object of the invention, being the provision of a novel mechanism by means of which a gravity closed gate or door is opened by the car or cage as it approaches from either direction the next succeeding floor, the car or cage after moving a certain distance beyond the floor permitting the release of the door or gate and its movement due to gravity to closed position. A further object of the present invention is the provision of novel trip actuating means, said means being located in the path of the car or cage, and means carried by the car or cage, which engage to move the trip a predetermined distance to cause the opening of the gate or door upon the approach of the car or cage during the ascent or descent thereof, such trip actuated means during the movement of the car or cage by the floor in either direction receding away and automatically releasing itself from the device carried by the car to permit the door or gate to close by gravity.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a front elevation of an elevator shaft constructed according to and embodying the present invention. Fig. 2 is a view taken at right angles thereto. Fig. 3 is a diagrammatic perspective view of the shaft carried mechanism connected to the gate or door. Fig. 4 is a perspective view of the guiding and releasing means for the shaft carried door or gate actuating mechanism. Fig. 5 is a perspective view of the two trips carried by the elevator car or cage. Fig. 6 is a plan view

showing the present application to a vertically movable gravity closed gate.

Referring to the drawings, the numeral 1 designates a shaft, which has mounted therein for ascent and descent, the car or cage 2, which is controlled by the hoisting cable 3, these features being merely indicative of any form of elevator and shaft and operating mechanism therefor.

Carried by the car or cage at any convenient place, and in the present instance shown as connected to the floor thereof, are the two oppositely actuated pivoted trip levers 4 and 5, the lever 4 being mounted to be held against movement downwardly during the ascension of the car and constituting a means for opening the doors or gates during the ascension of the car, while the device 5 is for actuating the door of the car during the descent of the car and permitted movement in the opposite direction to render the door actuating means inactive.

As the gate or door at each floor of the shaft is provided with the same mechanism, the description of one will suffice for all, the peculiar arrangement being diagrammatically shown in Fig. 3, and consisting of a cable 6, which has mounted upon one end or terminal, the weight 7. This cable is directed to pass over a pulley 8, and under and over the pulley 9 and extends vertically upward through the channel member 20 connected to the shaft adjacent the door or gate to be actuated over the upper pulley 10 and down again paralleling the last train thereof, to the lowermost pulley 11, the train then being extended upwardly and to the vertically disposed pulley 12. The cable 6 is there connected as at 13 to the two branch cables 6'-6'' which extend in opposite directions over the two horizontal pulleys 14-14' to the oppositely disposed pulleys 15-15'. Here these two cables 6'-6'' are extended forwardly and over the two vertical pulleys 18-18', the weights 19-19' being connected to the free terminals of such cables. The cables 6'-6'' at the point before they pass over the pulleys 18-18' are connected to the hangers 16-16' of the two horizontally disposed doors or gates 17-17', thus rendering it possible to operate two gates or doors at opposite sides of the shaft simultaneously. It is apparent that a single cable 6' may be employed to operate a single door 17. This door 17, as clearly shown in

Fig. 1, has its hangers 16 and 16' mounted upon the inclined track 17^a, so that when said door is released it will be closed by gravity assisted by the weight 19.

5 The casing member 20 constitutes a guide as before stated for the vertical portions of the cable 6 and disposed upon this cable 6 intermediate of the respective pulleys 9 and 10, and 10 and 11 are the blocks 21 and 22, 10 the block 21 constituting the means whereby the cable 6 is actuated to be pulled upon to open the gates 17-17' during the ascent of the car or cage 2, while the block 22 is operated to open the gate or doors upon the 15 descent of the car or gate.

As clearly shown in Figs. 2 and 4, the gate actuating block 21 is adapted to slide in the receptacle 26 of the channel 20 and upon the guide 23, said guide being provided with the reduced or inclined upper end 24, so that as the car or cage leaves the floor at which the gate or door is opened upon its ascent, the engagement of the trip 4 with the block 21 will carry the same upwardly and cause the same to ride off of the guide down the inclined end 24 and out of the path of the free end of the trip 4, the block 21 thus being automatically released from the trip 4 so that the gate may be 30 operated by the weights 19-19'. By this means, the gate is permitted to automatically close after the car leaves the floor.

The partition 25 divides the channel 20 into two chambers 26 and 27, the chamber 35 27 being provided with the guide 28, having its lower end inclined at 29, the guide 28 being adapted to guide the block 22 in its descent during the actuation thereof by the trip 5 during the descent of the car. Thus 40 it will be seen that as the car approaches the floor, in its descent, the trip 5 will engage the block 22 and pull down thereupon, so as to actuate the cable 6 in the same direction as when the block 21 is elevated due 45 to the engagement of the trip 4 during the ascent of the car. Thus with this structure, as the car approaches the floor, the block 22 is in a position upon the guide 28 to be engaged and moved with the trip 5 50 to open the doors or gates controlled thereby by the continued movement of the car below the floor causing the block 22 to ride upon the guide 28 and the inclined end 29 thereof at which time the same moves outwardly

and is released from the free end of the trip 55 5 to permit the gates or doors to close by gravity. It will thus be seen that by the peculiar arrangement of the cable 6 and the blocks 21 and 22, that the trips 4 and 5 will properly actuate the gates to open the 60 same as the car approaches the floor in either ascending or descending and that the continued movement of the car away from the floor in either direction will permit the 65 automatic closure of the gates.

As illustrated in Fig. 6, the present invention is applied to a vertically movable gate 30, the terminals 6^a and 6^b of the cable, which correspond to the cable 6, being passed over the pulleys 31 carried by the 70 shaft structure 1, and finally around the pulley 15^a, both terminals beyond this point being connected to the main cable 6 (not shown) but as heretofore illustrated in connection with a horizontally movable door or 75 gate. The gate 30 in this instance dispenses with the weight or weights 19.

What is claimed is:

The combination with an elevator shaft, a car and a gate for the shaft, of mechanism 80 for actuating the gate, including two oppositely movable pivoted trips carried by the car, a cable operably connected to the gate, two superposed pulleys about which the said cable passes, two trip actuated blocks 85 attached to the respective strands of the cable between the pulleys for consonant movement in opposite directions, one block being disposed to be engaged by one trip as the car moves in one direction and the other 90 is engaged by the other trip as the car is moved in the opposite direction, a race-way disposed adjacent to the blocks, and two projections carried by said raceway for engaging the blocks to hold them in the path 95 of the respective trips during the movement of the car, and whereby said blocks when moved are placed out of disengagement with the respective trips to release the gate as the car proceeds in either direction from 100 a landing.

In testimony that I claim the foregoing as my own, I have hereto affixed my signature in the presence of two witnesses.

GEORGE W. CARR.
